COLLAPSIBLE FLAT-LYING LUGGAGE HANDLE

Marton Szabo, Broome, Pa., assignor to Philadelphia Handle Company, Inc., Camden, N.J., a corporation of New Jersey

Filed Oct. 13, 1961, Ser. No. 144,903

5 Claims. (Cl. 190—58)

This invention relates to a handle for luggage, carrying cases and similar containers adapted to be pulled into an arched carrying position and to be readily collapsed into a flat non-carrying position against a wall of the container.

An object of this invention is to provide a flat-lying handle of the type disclosed in the Finkelstein Patent No. 2,962,138 which is equipped with a simple and effective means serving the function of releasably retaining the handle in the arched carrying position and in the flat-lying collapsed position while restraining rattling or undue vibration of the handle, and in which the necessity of providing ears on the guide housings, slots in the case wall to receive the ears and the considerable mechanical force heretofore required to clinch said ears about the case wall is obviated.

An important object of the invention is to provide a collapsible flat-lying rattle-free handle of the character described which employs spring members in the guide housings for retaining the handle in its up and down positions that are removably rather than fixedly secured in the guide housings thereby simplifying the manufacture and assembly of the handle, as well as the adjustment of the spring and replacement and repair of parts.

These and other objects of the invention will become more apparent as the following description proceeds in conjunction with the accompanying drawings, wherein:

FIGURE 1 is a longitudinal vertical sectional view through the handle in its collapsed flat-lying position taken on the line 1—1 of FIGURE 2;

FIGURE 2 is a sectional view taken on the line 2—2 of FIGURE 1;

FIGURE 3 is a longitudinal vertical sectional view similar to the right hand side of FIGURE 1 and illustrating the retention of the handle in the arched carrying position;

FIGURE 4 is a sectional view taken on the line 4—4 of FIGURE 3;

FIGURE 5 is a group perspective view of the guide housing, inner spring retaining member and spring in the form of the invention shown in FIGURES 1—4;

FIGURE 6 is a group perspective view of the inner spring retaining member and spring in another form of the invention; and

FIGURE 7 is a bottom plan view of the units of FIGURE 6 in an assembled condition.

Specific reference is now made to the drawings wherein similar reference characters are used for corresponding elements throughout.

The present invention relates to a handle construction of the type which is adapted to lie flat against a wall 10 of a piece of luggage to which it is attached, as shown in FIGURES 1 and 2, and to be pulled into an arched carrying position as shown in FIGURES 3 and 4. It is to be understood that the term "luggage" as used herein means briefcases, trunks, handbags, suitcases and any and all carrying cases, such for example as portable radios, phonographs, etc. The handle includes an elongated strip or blade of steel spring 12 suitable covered by leather, plastic or other material 14. At each end of the grip, a link is provided consisting of a concavo-convex rectangular member having transverse members

2

16 and 18 joined by longitudinal members 20 and 22. The transverse member 16 of each link passes through a conventional hinge loop, see FIGURE 1, and includes a bar which is riveted or otherwise secured as at 24 to each end of the spring 12.

The improved means to attach the ends of the handle to the wall 10 of the luggage will now be described, attention being particularly called to FIGURES 1—5. Since both ends of the handle are secured to the luggage by two of the same means, only one will be described hereafter.

A generally rectangular spring retainer member or housing 25 is provided having an upper wall 26 and side walls 28 and 30 and end walls 32 and 34 adapted to rest upon the luggage wall 10. The retainer member or housing is attached to the luggage wall via its upper wall 26 by any suitable means such as conventional staked in screws 36 and nuts 38. The side walls 28 and 30 are provided with holes 40, the end wall 32 with hole 42 and the other end wall 34 with holes 44 for a purpose soon to appear. If desired recesses may be used instead of holes.

The end wall 32 of the retainer member or housing confronts the end of the handle while the end wall 34 is remote therefrom. End wall 32 is provided with spaced openings 46 for slidably receiving the longitudinal members 20 and 22 of the link, the transverse member 18 of the link being disposed in the space between the upper wall 26 of the plate and luggage wall 10. A resilient member 48 is provided in the form of a trifurcated piece of spring steel, the central fork 50 having a depending flange 52 with a dimple or detent 54 protruding therefrom. The member 48 also has a rear flange 55 and spaced dimples or detents 56 protruding therefrom. The other forks 58 are spaced from the central fork providing a space through which the screws 36 extend, each fork 58 extending below the upper wall of the central fork and having an arcuate low point, node or crest 60.

For functional and decorative purposes caps or guide housings 62 are provided each having an upper wall 64 from which depends side walls 66 and 68 and front and rear end walls 70 and 72, the front wall having spaced slots 74. The front end wall 70 is provided with a dimple or detent 76 protruding therefrom and the side walls 66 and 68 are provided with similar spaced detents 78.

In operation, the spring member 48 is pushed into the housing 25 until the detents 54 and 56 of the end flanges 52 and 55 thereof engage in the holes 42 and 44 of the front and rear walls of said housing, there to be removably retained in position as such. If staked in screws 36 are used, these have already been in place and extend in the spaces between the end resilient forks 58. If other screws are used, these may be retained by the member 25 either before the spring is pushed thereinto or may be put in place afterwards. The links are then assembled on the units by making the longitudinal members 20 and 22 thereof extend through the openings 46 and then the screws 36 are passed through appropriate holes drilled in the case wall 10 to receive the closure nuts 38. The cap 62 is then slipped over the housing 25 until the detents 76 and 78 thereof engage in the holes 42 and 44 respectively of the member 26. While for decorative purposes no detents are shown in rear end wall 72 for engagement in the holes 44 in the rear wall of member 26, such may be used for additional security, if desired.

In operation, when the handle is collapsed to a position where it lies substantially flat against the luggage wall, each link except for its outer transverse member 16 is almost wholly confined within the area bounded by the end flanges 52 and 55 and the fork 50 of the spring member 48 and the luggage wall 10. In this position, the

edge of the inner transverse member 20 lies adjacent the rear of the fork 50 and the nodal bowed portions 60 of the forks 58 of the spring press down on the longitudinal members 20 and 22 of the link, preferably beyond the transverse center of the link in the direction of the end flange 52, as seen clearly in the drawings. Since the nodal portions 60 are spaced above the case wall 10 a distance equal or preferably less than the thickness of the longitudinal members of the link, thereby substantially restraining relative vertical movement between the link and the rear portion of the central fork 50.

When the handle is pulled or arched upwardly to the carrying position as shown in FIGURES 3 and 4, the inner transverse member 18 of the link moves beneath the nodal portions 60 of the spring member 48. The spring 12 in the handle grip, being arched or bowed, then exerts a force on the inner transverse members 18 urging them downwardly and outwardly against the luggage wall and free ends of the forks 58 whereby the handle is lockingly retained by a snap action in its arched carrying position. A positive, fairly strong downward force on the arched handle is required to make the transverse link member 18 clear the nodal portions 60 so that the handle may be collapsed.

In the modification shown in FIGURES 6 and 7, the spring member 80 is similar to element 48 previously described in that it is a trifurcated unit having a flat central fork 82 terminating in a protruding tip 84. The central fork is spaced as at 86 from the end forks 88 which are disposed below the central fork and include low or nodal points 90 adjacent one of their ends. At their other ends the forks or tines 88 end in the plane of central fork 82 and include rearwardly protruding tips 92.

The spring retaining member or housing 94 is similar to member 25 and therefore includes an upper wall 96 with spaced holes 98 to receive the heads of staked in screws to attach the same to the case wall 10, the screws being made to extend through the spaces 86 in the spring member 80. It also includes side walls 100 which may or may not have holes to receive the detents 78 of the caps 62, a rear wall 102 and a front wall 104 with a hole 106 therethrough.

In this modification, the spring member 80 is pushed into the retainer housing 94 and is there held in place by frictional engagement of the tips 84 and 92 against the front and rear depending walls 104 and 102 respectively. If desired, the width of the spring member 80 can be made to slightly exceed the distance between the inner surfaces of side walls 100 of retainer 94 to further provide for frictional engagement therewith. The cap 62 may then be placed over the member 94 and releasably held thereon by engagement of the detent 76 of the cap in the hole 106 in the front wall 104 of the member 94. Other holes in member 94 and detents in cap 62 may be provided for further security. The assembly of this modification on the hand grip and case wall and the functional behavior thereof with respect to the up and down positions of the handle are the same as for the modification of FIGURES 1-5 described hereabove.

Attention is called to the fact that the spring members 48 and 80 are made somewhat longer than the internal length of the housing 25 and 94 to put them under tension and thereby improve the resiliency of the spring arms 58 and 88.

While preferred embodiments of the invention have been shown and described herein, it will be understood that a skilled artisan may make minor variations in the combination and arrangement of parts without departing from the spirit of the invention and the scope of the appended claims.

I claim:

1. A collapsible luggage handle comprised of a longitudinally flexible hand grip portion capable of being arched to a carrying position and flattened to a non-carrying position, a spring in said hand grip portion normally

urging the same into said flattened position, links connected to opposite ends of said hand grip portion and means slidably mounting each link upon a luggage wall, said means including a housing adapted to be secured upon the luggage wall including an upper wall and depending end walls adapted to bear on the luggage wall, one of said end walls being slotted to slidably receive said link, a resilient member, means removably securing said resilient member in said housing, said resilient member including at least one portion bowed away from said upper wall, the crest of said bowed portion bearing on said link to prevent vertical rattling thereof in the housing when said handle is in the flattened position, said spring in said hand grip portion urging a portion of said link against said bowed portion when said handle is in the arched carrying position to hold said handle in said carrying position when said handle is released, said resilient member including depending end walls and said means removably securing said resilient member in said housing including interengaging apertures and detents between adjacent end walls of said resilient member and said housing.

2. A collapsible luggage handle comprised of a longitudinally flexible hand grip portion capable of being arched to a carrying position and flattened to a non-carrying position, a spring in said hand grip portion normally urging the same into said flattened position, links connected to opposite ends of said hand grip portion and means slidably mounting each link upon a luggage wall, said means including a housing having an upper wall and depending end walls adapted to bear on the luggage wall, one of said end walls being slotted to slidably receive said link, a resilient member having a pair of spring arms spaced from a central portion, elongated members carried by said upper wall of said housing and passing through the spaces so formed and adapted for attachment to a luggage wall, said resilient member including end walls, and interengaging detents and recesses removably connecting the corresponding end walls of said resilient member and said housing, said spring arms including portions bowed away from said upper wall, the nodes of said bowed portions bearing on said link to prevent vertical rattling thereof in said housing when said handle is in the flattened position, said bowed portions coating with said hand grip spring on said links to hold said handle in its arched carrying position.

3. A collapsible luggage handle comprised of a longitudinally flexible hand grip portion capable of being arched to a carrying position and flattened to a non-carrying position, a spring in said hand grip portion normally urging the same into said flattened position, links connected to opposite ends of said hand grip portion and means slidably mounting each link upon a luggage wall, said means including a housing adapted to be secured upon the luggage wall including an upper wall and depending end walls adapted to bear on the luggage wall, one of said end walls being slotted to slidably receive said link, a resilient member engageable with said link to releasably and selectively retain said handle in said arched carrying and flattened non-carrying positions, said resilient member including depending end walls, and interengaging detents and recesses between adjacent end walls of said resilient member and said housing to removably secure said resilient member to said housing.

4. A collapsible luggage handle comprised of a longitudinally flexible hand grip portion capable of being arched to a carrying position and flattened to a non-carrying position, a spring in said hand grip portion normally urging the same into said flattened position, links connected to opposite ends of said hand grip portion and means slidably mounting each link upon a luggage wall, said means including a housing adapted to be secured upon the luggage wall including an upper wall and depending end walls adapted to bear on the luggage wall, one of said end walls being slotted to slidably receive said

link, a resilient member engageable with said link to releasably and selectively retain said handle in said arched carrying and flattened non-carrying positions, said resilient member including end portions having detents engageable with adjacent end walls of said housing to removably secure said resilient member to said housing.

5. The combination of claim 3 wherein said recesses are apertures through the end walls of said housing and said detents are protuberances on the end walls of said resilient member which extend into said apertures from the inside of said housing, and a cap encompassing said housing having upper, side and end walls and a protuberance in at least one end wall of said cap extending into

one of said apertures in an adjacent end wall of said housing from the outside thereof to removably secure said cap to said housing.
